UNITED STATES PATENT OFFICE.

ALBERT L. DIRST, OF SEWARD, ILLINOIS.

IMPROVEMENT IN CLOD-FENDERS.

Specification forming part of Letters Patent No. 135,896, dated February 18, 1873.

To all whom it may concern:

Be it known that I, ALBERT L. DIRST, of Seward, in Kendall county and State of Illinois, have invented certain Improvements in Shields or Clod-Fenders for Cultivators, of which the following is a specification:

My invention relates to the peculiar construction of the device whereby the fender-bars of same may be set at any distance apart to admit of as much or little earth passing between them as is desired, and also that the shield may be set at any desired angle with the plow-beam, so as either to run parallel with the same or scrape the earth along to or from the plant, as may be desired, and at the same time fend the plant from the large clods that the plow might turn onto the same.

Figure 1 is a perspective view of the device attached to a plow. Fig. 2 is a perspective view of one of the fender-bars of the device. Fig. 3 is a perspective view of the device by means of which the shield is attached to the plow-beam; and Fig. 4 is a plan view on the top of the shield.

The shield or clod-fender is constructed of metal or any suitable material in about the form shown in Fig. 1, only it may have any number of fender-bars S desired, instead of two shown.

The shoe a terminates at its upper end in an elbow, c, as shown, which attaches to the elbow r, which attaches by means of a bolt to the plow-beam B, as shown in Fig. 1. The vertical portion of the shoe a is furnished with a slot, x, extending from where the shoe touches the earth to the elbow c, which slot receives the forward ends of the fender-bars S S, as shown in said figure. The bars S S are held in place by bolts passing through the transverse slots n through the shoe a, as shown.

It will be perceived that inasmuch as the

fender-bars S rest upon the shoe a at the angles or offsets o, that by raising up the forward ends of the said bars in the slot x, by means of loosening the bolts in the slot n passing through the same, the rear ends of the said bars may be elevated or depressed at will, so they may be set at any distance apart from each other, so they will appear to radiate from a common center like the spokes in a wheel, or may be arranged parallel with each other at any distance apart, by means of which any desired amount of earth may be allowed to fall between them next to the plant. Fig. 4 shows more particularly the construction of the device in that regard.

The elbow c of the shoe a is furnished with transverse slots t, through which pass the bolt m through the elbow r, by means of which they are attached to each other. The use of the slots t is to allow of an adjustment of the shoe a, so it will run parallel with the beam, or at any other angle desired, as before stated, and for the purpose described.

The device may be attached to any kind of a plow or cultivator, but is designed to be used on corn or cotton cultivators.

Claim.

Having thus described my invention, what I claim as new, and desire to secure by Letters Patent, is as follows:

The shoe a having the slots n and t, in combination with the bent adjustable bars S, arranged as shown, whereby the spaces between the bars and the distance and angle from the plows may be regulated at pleasure, as and for the purposes set forth.

ALBERT L. DIRST.
